COMPUTING MACHINE

Filed Feb. 2, 1928

UNITED STATES PATENT OFFICE

FREDERICK A. HART, OF NEW BRITAIN, CONNECTICUT, ASSIGNOR TO REMINGTON TYPEWRITER COMPANY, OF ILION, NEW YORK, A CORPORATION OF NEW YORK

COMPUTING MACHINE

Application filed February 2, 1928. Serial No. 251,332.

My invention relates to computing machines and especially to combined typewriting and computing machines.

The invention has for its principal object 5 to provide certain improvements in the clearance-proof mechanism of computing machines to the end that the printed record shall show automatically whether the total or balance written on the paper and cleared from 10 the computing mechanism was a positive balance or a negative one, or, as it is more commonly expressed in bookkeeping, whether the balance was a debit or a credit balance. The machine is equipped with a clearance-proof key, which in the case of the ordinary sort of balance (usually a debit balance) will print one sign, such as a star; but in case the balance copied was a negative balance it will automatically print another 15 clearance sign, such, for example, as the letters CR.

To the above and other ends the invention consists in certain features of construction and combinations and arrangements of parts, 20 all of which will be fully set forth herein and particularly pointed out in the claims.

One form of the invention is illustrated in the accompanying drawings, in which

Fig. 1 is a conventional perspective view of 25 those parts of a Remington combined typewriting and computing machine that are more especially and directly concerned with the invention;

Fig. 2 is a plan view in section of a portion 30 of the mechanism; and

Fig. 3 is a front view in section on the line 3—3 of Fig. 2.

The invention is shown applied to a Remington cross-footing combined typewriting 35 and computing machine of the kind that is now being manufactured and sold, and which is well known in the art. The greater part of the mechanism is substantially like that described in the patent to John C. Wahl, No. 45 1,270,471, dated June 25, 1918, but with some exceptions that will be pointed out.

The machine includes a Remington No. 12 typewriter (that shown in the said Wahl patent is a Remington No. 11 typewriter) having 50 attached to it the computing mechanism

described in the Wahl patent. Said mechanism includes a main truck connected with a typewriter carriage and on which may be mounted a suitable number of vertical totalizers, and a cross truck on which is mounted a cross-totalizer 1. Each vertical-totalizer is constructed with a foot, and the cross truck is provided with a pick-up beam which, as the vertical totalizer moves into the adding column position, is picked up by said foot, causing the cross totalizer to move across its actuating master wheel in unison with the vertical totalizer. The vertical master wheel can be reversed by a hand lever, not shown, and the cross master wheel can be reversed by means of cams mounted on the several vertical totalizers so as to cause the cross totalizer 1 to add in one predetermined column and to subtract in another. In some classes of work it is customary to have a vertical column set aside for the writing therein of the balance disclosed in the cross totalizer, and when that is done the vertical totalizer in that column is equipped with a subtract cam so that the total will be subtracted out of the cross totalizer when it is written. If this be correctly done the operation will clear the cross totalizer. This totalizer as now manufactured is equipped with clearance testing mechanism such as that described in the patent to A. F. Poole, No. 1,483,679, dated February 12, 1924, such mechanism comprising a feeler spring-pressed against the dial pinions and adapted to move when all of the dials stand at zero, and said feeler controlling 55 a finger 2 projecting upward from the totalizer and occupying the rear position shown in Fig. 1 when the totalizer is clear, but moving forward when the totalizer is not clear. When in its clear position, the finger 2 is adapted on the jump-back of the cross totalizer to pass under a cam 3 secured to a lever arm 4 which is pivoted at 5 to a sheet metal frame-piece 6 which is secured to the main casting of the machine, the lever 4 being urged downward not only by its own weight 60 but also by a spring 7. In case the totalizer is not clear the finger 2 moves in front of the cam 3 and does not raise it. As at present manufactured the framepiece 6 has a shelf 65 70 75 80 85 90 95 100

bent off therefrom and serving to limit the downward motion of the lever 4. The Poole patent cited contains certain devices for controlling the lever 4 which are omitted in the present instance, with the result that said lever 4 occupies its lower position at all times except when the cross totalizer is in its jumped-back or initial position shown in Fig. 1, and is clear.

The mechanism shown in the present instance and cooperating with the lever 4 is, except as will be herein pointed out, the same as that described in my application for Letters Patent filed October 9, 1925, Sr. No. 61,471. Said lever 4 has a bent-off ear 10 slotted to be guided by a portion of the frame piece 6, and said horizontal ear 10 is embraced by the forked end of a lever 11 which is pivoted at 12 to the stationary framework and is provided with a downwardly projecting arm ending in a leftward projecting finger 13. This finger extends through a guide slot in one of the front-to-rear sheet metal frame plates of the Wahl computing mechanism and to the left-hand side of said frame plate a bell crank 14 is pivoted at 15, the upstanding arm of said bell crank being in such a position that when the lever 11 is held up by reason of the clear condition of the totalizer as shown in Fig. 1, the bell crank can rock clockwise in Fig. 1; but when the lever 4 is down as it always is when the cross totalizer is not clear, then the finger 13 projects into the path of said bell crank and locks the latter against operation. A vertical link 16 is connected at its upper end to the horizontal arm of the bell crank 14 and at its lower end to a clearance-proof key lever 17, sometimes called a "star key". This key has its button 18 in the keyboard of the machine, usually at or near the right hand side thereof, and the lever 17 is shaped about the same as one of the ordinary printing levers of the typewriter, being pivoted at its rear end at 20. The lever 17 has pivoted thereto at 21 an up-standing link 22 having a cross pin 23 in its upper end. Two adjacent type bars 24 and 25 carry types for printing respectively two special signs, such as the two letters "CR" and a star as indicated in Fig. 1. These two type bars are operated by two bell cranks 26 and 27, the upright arms of which are like those usual in the Remington machine and like them pivoted on a cross wire 28. The horizontal arms of these two levers have however been modified. The lever 26 is cut off at 30 and the lever 27 is made longer than the lever 26 but has an open-ended slot 31 therein, forward of which is a horizontal part 32. The link 22 occupies the plane between these two bell cranks. In Fig. 1 said link is shown in its forward position with the pin 23 resting on the part 32 of the lever 27, so that if the key 18 were to be operated thereby

and the type bar 25 would print a star, indicating that the machine had just been cleared from a positive or debit balance. The link 22 can, however, be swung rearward from the position shown in Fig. 1 in which event the right-hand end of the pin 23 would come over the notch 31 and the left-hand end of said pin would extend over the bell crank 26. If in that event the key 18 were depressed the bell-crank 26 and type bar 24 would be operated and a "CR" would be printed. 75

The link 22 is controlled by the so-called "credit balance" mechanism of the machine which will now be described.

The Remington machine contains a double link 33 corresponding to that described in the Wahl patent cited and therein numbered 384, 385. This link normally occupies the left-hand position shown in Fig. 1 and it is so connected that if it be moved longitudinally toward the right it will reverse the direction of rotation of both the vertical and the cross master wheels, irrespective of the previous setting of each of said wheels. If for example the cross master wheel had been set for addition the motion of this link toward the right would set it for subtraction, and if said cross master wheel had been set for subtraction the rightward motion of this link would reverse it and cause it to add. 90 This link operates in the same way in the present machine as described in the Wahl patent but it is here shown controlled by mechanism described in my prior Patent No. 1,587,304 dated June 1, 1926. Said link is pivoted to the upstanding arm of a bell crank 34 pivoted at 35 in the actuator framework and having a horizontal arm which is connected by a link 36 with a "Correction key" lever 37 pivoted at 38. Any suitable spring 40 may be employed to hold the parts in their normal positions with the link 33 in its left-hand position. The lever 37 is prolonged rearwardly where it is provided with a headed pivot 41 working in a vertical slot 42 in a vertical link 43 which at its lower end is pivoted to the rightward extending arm 44 of a lever having also a leftward extending arm 45. The lever 44 is mounted on a fore-and-aft extending rock shaft 46 which at its forward end is journaled in a frame plate 47 secured to the left-hand front post 49 of the typewriter frame. A three-armed lever 48 is pivoted at 50 to the lever arm 45 and to the left of the pivot 50 it has a "Credit balance" key 51 secured thereto and at the right of said pivot a release key 52. The third arm of the lever 48 extends downward in a curve and it has in it an arc-shaped slot 53 which rides over a pin 54 projecting from the plate 47. The upper left-hand end of the slot 53 has a locking off-set 55. The construction is such that if the credit balance key 51 be depressed as far as it will go the wall of the slot 53 will slide over the pin 54 until the 130

end of said slot reaches said pin whereupon the pressure of the finger will cause the lever 48 to rock and will cause the notch 55 to engage the pin 54 and lock the lever 45 down against the tension of the spring 40. The lever can be released at any time by a tap on the key 52 which will rock the lever 48 in the opposite direction. The depression of this key permits spring 40 to move the link 33 leftward and restore the master wheels to their original setting. Whenever the cross totalizer is found to display a negative or credit balance, the key 51 is depressed before copying such balance. Ordinarily the cross master wheel has been automatically set for subtraction at that time so that the operation of the key 51 causes the master wheel to be set for addition, the negative balance would be added into the cross totalizer and would clear the latter enabling the clearance proof key 18 to be operated.

The shaft 46 is the one which in the Remington machine controls the throw of the ribbon vibrator, and in case the machine is equipped with a two-color ribbon it controls the color of the printing. To this end said shaft has depending therefrom an arm 56 to which is pivoted a link 57 extending to the ribbon mechanism. This latter may be of the sort described in the patent to John H. Barr No. 1,153,668 dated September 14, 1915. The showing in the drawing of the shaft 46, arm 56 and link 57 are intended as a conventional representation of a bi-color ribbon mechanism. This mechanism has heretofore been used in the Remington machine, and it causes a credit balance to be printed in red; but in these machines one or more carbon copies are usually printed, and these are not affected by the color mechanism and therefore they would show no visible distinction between a credit and a debit balance. This distinction on the carbon copies is supplied by my improvements.

According to the present invention, the shaft 46 is connected to control the action of the link 22. To that end said shaft may have fixed thereon a horizontal arm 58 which is connected by a vertical link 60 with an arm 61 projecting forward from a rock shaft 62 suitably pivoted in the base of the typewriter and extending from side to side thereof just above the printing key levers. Near the right-hand side of the machine this shaft has fixed thereto an upstanding arm 63 which is connected by a link 64 with the link 22 hereinbefore described. The construction is such that when the shaft 46 is in the position indicated in the drawings the link 22 occupies its forward position in which the key 18 would be caused to print a star. The depression of the key 51 would rock the link 22 to its rear position where it would cause the printing of "CR" on depression of the key 18.

As described in my prior Patent No.

1,587,304 above referred to, the lever 44, 45 is not fixed to the shaft 46 but is connected with said shaft yieldingly so that whereas said lever and said shaft ordinarily rock together still by the application of a little extra force the one can be rocked independently of the other. Said shaft has fixed on its forward end a hub 65 from which project wings 66, that can be manipulated by the fingers of the operator. As shown in Fig. 2, said hub has a longitudinal hole 67 in which is seated a compression spring 68 acting on a ball 70, pressing said ball part-way into depressions 71, Fig. 3, in the lever 44, 45. This spring-pressed ball couples the shaft 46 and the lever together sufficiently well so that they ordinarily rock together, but when the key 51 is locked in its depressed position the wings 66 and the shaft 46 can be turned by hand clockwise, forcing the ball 70 out of one of the depressions 71 and into the other. The relative motion between the shaft and the lever is limited by a pin 72, Fig. 1, projecting from the shaft 46 into a notch 73 in the hub of the lever 44, 45, said notch being wider than the pin. This construction is not essential but it is useful because it is sometimes desired to depress the key 51 for some other purpose than that of copying a credit balance and of such a sort that it is not desired to write the number in red. In that case the key 51 can be depressed and the wing 66 moved clockwise whereupon the cross master wheel will be reversed, but the printing will be in black. In all instances, however, where the key 51 is operated preliminarily to the printing of a credit balance the shaft 46 is rocked for red printing and the action of the key 18 will therefore be modified to cause said key to print "CR" instead of a star. It will thus be seen that ordinarily the shifting of the link 22 to select between two different clearance signals to be printed, is controlled by the mechanism for reversing the master wheel, but that this selection can be made to harmonize with the color of the printing irrespective of the setting of the master wheel.

So far as I am aware it is broadly new in a combined typewriting and computing machine equipped with a clearance proof key of the sort sometimes called a "star key" to provide means for causing this key to print one character to indicate clearance of one kind of balance, and another character to indicate clearance of another kind of balance.

Various changes may be made in the details of construction and arrangement without departing from the invention.

What I claim as new and desire to secure by Letters Patent, is:—

1. The combination of a totalizer, clearance-proof mechanism for said totalizer including two types, and means for operating said types, said operating means controlled as to operativeness by the state of said totalizer.

as to clear and not clear and controlled selectively according as the balance cleared from said totalizer was positive or negative.

2. The combination with a totalizer having means for testing its state as to clear and not clear, of two clearance-proof types, and means for operating said types selectively according as the balance cleared from said totalizer was positive or negative, said means being controlled as to operativeness by said clearance testing means.

3. The combination with a totalizer and means settable to control the operation of said totalizer to clear therefrom a positive balance and a negative balance, of clearance-proof mechanism including two types, means for operating said types, said means being controlled as to its operativeness by the state of said totalizer as to clear and not clear, and means whereby said operating means acts selectively on said types depending upon the setting of said settable means.

4. The combination with a totalizer, means settable to control the clearing of said totalizer positively or negatively as the case may be, and clearance-proof mechanism including two types, a key for operating said types, means for locking said key in case said totalizer is not clear, and means for connecting said key with one or the other of said types according to the setting of said settable means.

5. The combination with a totalizer, a device settable in one position to cause said totalizer to be operated additively and in another position to cause said totalizer to be operated subtractively, and means for testing said totalizer for clearance, of a clearance-signal-printing key controlled as to its operativeness by said clearance testing mechanism, two clearance proof types, and connections from said key to said types including a link controlled by said settable device, said link connecting said key with one of said types in one setting of said settable device and with the other of said types in the other setting of said types.

6. In a combined typewriting and computing machine, the combination with a totalizer having means for testing its state of clear and not clear, and a reversing device to reverse the direction of operation of said totalizer, of two type bars each carrying a clearance signal type, a clearance-proof key, a lock to prevent operation of said key when said totalizer is not clear, a connection from said key to said type bars, and means whereby said setting means controls the connection of said key to one of said type bars in one setting of said settable means and to the other type bar in the other setting of said settable means.

7. In a combined typewriting and computing machine, the combination with a totalizer, printing means, a credit-balance key, means whereby said credit-balance key may

control the color of the printing, and means whereby the color of the printing may be restored to normal if desired even though said credit-balance key is in its abnormal position, of clearance-proof mechanism for said totalizer including two types, means for operating said types, said operating means controlled as to operativeness by the clear state of said totalizer, and means whereby said operating means is controlled selectively as between the two types by the color controlling mechanism.

Signed at the borough of Manhattan, city of New York, in the county of New York and State of New York, this 31st day of Jan., 1928.
